UNITED STATES PATENT OFFICE.

JAMES J. BYERS, OF GULFPORT, MISSISSIPPI, ASSIGNOR OF ONE-THIRD TO WILLIAM ANDREW DAVIS AND ONE-THIRD TO FLETCHER WILLIAM BEALL, OF GULFPORT, MISSISSIPPI.

WOOD SATURATING AND COATING APPARATUS.

No. 858,950.

Specification of Letters Patent.

Patented July 2, 1907.

Application filed February 27, 1906. Serial No. 303,230.

To all whom it may concern:

Be it known that I, JAMES J. BYERS, a citizen of the United States of America, residing at Gulfport, in the county of Harrison and State of Mississippi, have 5 invented new and useful Improvements in Wood Saturating and Coating Apparatus, of which the following is a specification.

This invention relates to wood saturating and coating apparatus, and particularly to an apparatus for 10 impregnating and coating shingles and wooden strips or articles with a preservative liquid in such a manner as to fill the pores to preserve the wood to a maximum degree, as well as to impart a durable finish to the surface of the wood.

15 The object of the invention is to provide an apparatus of this character, whereby the wood to be treated may be preliminarily subjected to the action of steam to open its pores and relieve it from the sap and acids contained therein, and then treated with the preservative liquid to force it therein under pressure so 20 as to close the pores and cover the surface.

The accompanying drawing shows partly in elevation and partly in central vertical section a wood saturating apparatus constructed in accordance with my 25 invention.

In the drawing, the numeral 1 designates a receiver or chamber to contain the shingles or other wooden articles to be treated, said receiver being of rectangular or any other suitable form and composed of some 30 suitable material which will be air-tight and not affected to an appreciable extent by the action of steam. In the present instance I have shown said receiver in the form of a rectangular metallic box having at one side an inlet opening for the introduction and removal of the goods, said opening being closed by an approved type of door 2. The receiver is further provided adjacent to its upper end with a test valve or cock 3 adapted to be opened to permit of the exhaust of air therefrom when steam is admitted thereto to 35 enable the operator to determine when the receiver is completely filled with steam. A steam supply pipe 4 leading from a boiler or other source of steam supply extends above the receiver and is connected to the upper end thereof through the medium of a pipe 5 containing a valve 6; whereby the supply of steam to the receiver may be regulated. Arranged at any suitable point adjacent to the receiver is a reservoir 7 for the preservative liquid, comprising a cylinder closed at its upper and lower ends by heads 8 and 9 detachably fastened thereto in any preferred manner. This 45 reservoir is provided with an ordinary type of gage 10, whereby the level of the paint contained therein may be determined at any time. Arranged within the reservoir is a coil 11 communicating at its upper end by 50 a pipe 12 extending through a plug or stuffing box 13

in the head 8 with the adjacent end of the steam supply pipe 4, a valve 14 being disposed between the juxtaposed ends of said pipes to regulate the supply of steam to the coil. The impregnating and coating liquid employed may be composed of any desired 60 preservative oil, such as pine oil, mixed or not with any desired pigment, and is introduced into the receiver through a filling opening in the head 8, which opening is normally closed by a cap 15. The liquid is kept heated to a desired degree of temperature to 65 prevent it from being supplied at too low a degree of temperature to the receiver 1 by the heat radiated from the coil 11 emanating from the steam introduced thereto. A shaft 16 extends vertically within the reservoir and is journaled in bearings 17 and 18 carried by the upper and lower heads and extends through the bearing 18 and is provided with an actuating crank handle 19. The inclosed portion of the shaft extends through the coil and carries a series of stirrer blades 20 arranged to rotate within the coil, 70 whereby the liquid may be readily and conveniently agitated to insure a thorough admixture of its ingredients prior to its passage into the receiver 1 for use.

The lower end of the coil is connected with a by-pass or auxiliary steam supply pipe 21 which extends 80 through a plug or stuffing box 22 in the bottom head 9, and is provided adjacent thereto with a valve 23 through which the water resulting from the condensation of the steam in the coil may be drawn off whenever required. The said pipe 21 connects with the 85 steam supply pipe 4 at a point adjacent to the valve 14 and is provided between said supply pipe and the valve 23 with a valve 24, whereby the supply of steam to the coil therethrough may be controlled.

A discharge pipe 25 leads from the bottom of the receiver and connects with a drain pipe 26, whereby the contents of the reservoir may be drawn off whenever desired. A valve 27 is interposed between these pipes to cut off connection between them. Leading from the pipe 25 to the bottom of the receiver 1 is a 95 pipe 28 which extends at an upward angle of inclination between said pipe 25 and the receiver and is provided with an intermediate cut-off valve 29. A bypass pipe 30 bridges across the valve 29 and has its terminals connected with the pipe 28 on opposite sides 100 of said valve and provided with check valves 31 and 32. Arranged in the pipe 30 between the check valves is a pump cylinder 33 communicating at its lower ends with the portions of the pipe 30 and having operatively arranged therein a piston 34 operatively connected 105 with an actuating lever 35.

In the operation of the apparatus, the valves 27 and 29 are closed to cut off communication between the reservoir, drain pipe and receiver, and the valve 6 is closed to prevent the inlet of steam to the receiver. 110

The wood to be treated is introduced into the receiver and the latter hermetically sealed by its door 2, after which the valve 6 is opened to allow steam to enter the receiver from the pipe 4. The valve 3 is then 5 opened to allow air to exhaust from the receiver and is closed when the latter is completely filled with steam. The wood is exposed to the action of the steam for a desired period, or until it is softened and its pores opened and the sap and acids caused to exude 10 therefrom, after which the supply of steam to the receiver is cut off. While the wood is still in a heated state and with its pores open the pump piston 34 is operated to draw the preservative liquid from the reservoir and discharge it under pressure into the receiver. 15 Upon the up stroke of the piston the liquid will be drawn from the section of the pipe 28 between the valve 29 and pipe 25 into the pump cylinder 33, the check valve 31 opening to allow it to enter the cylinder and then closing to prevent its return. Upon the 20 down stroke of the piston the liquid previously drawn into the pump cylinder will be discharged through the valve 32, which will open under the pressure thereof, into the section of the pipe 28 between the receiver and valve 29 and thence into said receiver, 25 the valve 32 closing to prevent any of the liquid from passing back to the pump cylinder. By this means a continuous supply of liquid may be forced under pressure into the receiver 1, into contact with the treated wood contained therein, the liquid being forced into 30 the pores of the wood and over the surface of the same. As the liquid is kept in a heated condition, it will, of course, be understood that it will penetrate the pores of the wood to a maximum extent and will flow in a uniform coating over the same. After a sufficient 35 amount of liquid is applied, the door 2 is opened and the wood allowed to remain in the receiver until the liquid is dry or removed therefrom before drying. As a result of this process of treatment the sap and acids contained in the wood will be extracted therefrom 40 and the wood saturated and coated with a liquid substance which will preserve it for an indefinite period from decay, and as such substance both penetrates and coats the wood it will not peel or scale off and will keep its luster and prevent moisture from penetrating 45 into the wood under all conditions of service. By using a pure pine oil as a vehicle for the preservative composition in the treatment of shingles, the nails used to secure the shingles to the roof will be constantly lubricated and prevented from rusting and en- 50 larging the opening in the shingle through which they pass.

It will be understood that either valve 14 or 24 may be kept closed, while the other is opened to admit steam to the upper or lower end of the coil, and that by opening both valves steam may be allowed to enter the coil at the top and bottom thereof until the coil is completely filled and a balancing of the steam pressures is effected, whereby condensation will be retarded and steam allowed to enter at both points to automatically take the place of that lost through condensation. The 60 arrangement of the pipes 20 and 21 further provides for the independent use of either of them in the event of the other becoming choked, leaking or otherwise being rendered inoperative. By simply arranging the bottom of the receiver above the bottom of the reservoir, the surplus liquid in the receiver may be allowed to exhaust by gravity through the inclined pipe 28 back to the reservoir upon opening the valve 29.

Having thus described the invention, what is 70 claimed as new, is:—

1. A wood saturating apparatus comprising a receiver, a reservoir for the preservative liquid, a pipe connection between the bottoms of the receiver and reservoir for the flow of the preservative liquid from said reservoir to said receiver, said pipe being provided with a controlling valve and inclined for the return of the excess liquid from the receiver to the reservoir by gravity, a by-pass having valved branches connected with said pipe on opposite sides of said controlling valve, a pump between said branches for forcing the preservative liquid from the reservoir to the receiver, a heating coil within the reservoir, a steam pipe connection between a source of steam supply, the receiver and one end of the coil, a supplementary steam pipe connection between said pipe and the opposite end of the coil, said supplemental pipe being provided with a vent for condensed steam, and valves controlling said pipes, said valves being arranged for the admission of steam to either end of the coil.

2. A wood saturating apparatus comprising a vertical receiver, a vertical reservoir for the preservative liquid, a heating coil disposed vertically within the reservoir, a supply pipe leading from the lower end of the reservoir to the lower end of the receiver, said pipe being provided with a controlling valve, a by-pass pipe connected with the supply pipe on opposite sides of said valve, said pipe comprising branches, each having a cut-off and a check valve, a pump disposed between said branches, a steam supply pipe connecting with the receiver and the upper end of the coil and having controlling valves, and a branch pipe connecting said steam pipe with the lower end of the coil and provided with a controlling valve and drip cock, substantially as described.

In testimony whereof I affix my signature in presence of two witnesses.

JAMES J. BYERS.
